(57) **CLAIM**

The ornamental design for a smartphone display screen with graphical user interface, as shown and described.

DESCRIPTION

FIG. 1 shows a view of a smartphone display screen with graphical user interface;

FIG. 2 shows an enlarged view of a second embodiment thereof, shown separately from the smartphone for clarity of illustration; and,

FIG. 3 shows another enlarged view of a third embodiment thereof, shown separately from the smartphone for clarity of illustration.

The dashed lines are for the purpose of illustrating the display screen and form no part of the claimed design. The remaining broken lines of the graphical user interface namely, the “mYcore smartcoat” text, the central icon, the two circular slide buttons, the “0%” and “60%” text, the lightning bolt, and the “mYcorecontrol technology inside” text, form no part of the claimed design.
